Primary Examiner — Elizabeth A. Albert(74) *Attorney, Agent, or Firm* — Salter & Michaelson(57) **CLAIM**

The ornamental design for a garden tray, as shown.

DESCRIPTIONFIG. 1 is a perspective view of a garden tray;
FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof; and,

FIG. 7 is a rear elevational view thereof.

The broken lines in FIGS. 2 and 3 are included to show portions of the garden tray that form no part of the claimed design.
